UNITED STATES PATENT OFFICE.

DAVID B. KERR, OF PHILADELPHIA, PENNSYLVANIA.

WOVEN FABRIC.

SPECIFICATION forming part of Letters Patent No. 353,790, dated December 7, 1886.

Application filed July 31, 1885. Serial No. 173,178. (No specimens.)

To all whom it may concern:

Be it known that I, DAVID B. KERR, a citizen of the United States, residing at Philadelphia, in the county of Philadelphia and State 5 of Pennsylvania, have invented a new and useful Improvement in Woven Fabrics; and I do hereby declare that the following, taken in connection with the annexed drawings, is a full, clear, and exact description thereof, and is 10 sufficient to enable others skilled in the art to practice my invention.

The object of my invention is to produce in a woven fabric a variety of shades of color in the pattern or figure by a new way of inter- 15 weaving the warp and weft threads, avoiding the expense of extra colors in the warp and weft threads.

My invention consists in the combination of two warps of the same color with two or more 20 colored weft-threads. The warp-threads are so arranged in the loom-harness as to work in pairs, with a binder warp thread in the center of each pair, as will be hereinafter described.

Reference is had to the annexed drawings, 25 making a part of this specification, in which Figures 1 to 14 represent cross-sections showing various collocations of the warp and weft threads of a fabric woven according to my invention. They are not intended to represent 30 the threads as of the proper size or as driven up in a finished fabric, but are intended to aid in defining the character of the fabric and the preferred manner of making the same.

In describing the warp-threads as "up" and 35 as "down," it is to be understood that they are shown above or below particular shots of weft.

My invention is especially applicable to all fabrics with one color for warp-threads and 40 different colors for weft-threads, such as upholstery fabrics, shawls, carpets, &c.

In weaving my improved fabric I prefer to use the well-known common Jacquard loom, provided with a shuttle-box motion to work 45 two or more colors, pick and pick, and two warp-beams.

Referring to the drawings, similar letters and figures of reference refer to similar parts throughout the several views.

50 A and B represent the weft-threads, 1 and 2 the warp-threads. The warp-threads 1 I call

the "binder" warp. These threads are all wound on one beam. The warp-threads 2 I call the "figuring" warp. These threads are all wound on another beam. In the warps there 55 are two figuring-threads to one binder-thread. These warp-threads are drawn in the Jacquard harness in the following order: A figuring warp-thread, 2, then a binder warp-thread, 1, then a figuring warp-thread, 2. This makes a 60 pair of figuring warp-threads with one binder warp-thread in the middle and three warp-threads in a set. This manner of drawing in the warp-threads in pairs and sets is repeated the full width of the warps.

65 The harness-cords connecting the lifting-bars or trap-boards of the Jacquard that operate the figuring warp-threads 2 may be connected single or double—that is, if double, each of the two heddle-eyes of a pair of the 70 figuring warp-threads 2 may be connected so as to be operated by one needle of the Jacquard. This arrangement increases the capacity of the machine one-third.

In selecting the colors of yarn to produce my 75 improved woven fabric, I take two warps having threads all of the same color, and two wefts, each of a different color. The binding warp-threads 1 I prefer to be finer than the figuring warp-threads 2, as the binder warp- 80 threads are not intended to show much in the shading of the figures.

In describing the manner of producing the shades of colors in my improved woven fabric, we will suppose that the two warps 1 and 85 2 are all black, the weft A yellow, and the weft B red.

The manner of lifting the warp-threads and inserting the weft to produce different shades of colors is as follows: For the first shot of 90 weft A, (yellow,) Figure 1, one half of the figuring-warps and binder-warp are up and half down. For the second shot, Fig. 1, all the figuring warp-threads are up, and the binder warp-threads have not changed from the first 95 pick. The weft in this second shot is B, (red.) For the third shot A, Fig. 2, half of the figuring and binding warp is up and half down. For the next or fourth shot B, Fig. 2, all the figuring warp-threads are up, and the binding 100 warp-threads are not changed from the third shot. The four shots shown in Figs. 1 and 2 will

give or make a checker pattern of black and yellow on the face and a red plain weave on the back. For the first shot, in Fig. 3, the warp-threads are evenly divided, half up and half down; but it will be noticed that the binder warp-threads 1 of each pair 2 are up where the pair 2 is down, and down where the pair 2 is up. For the second shot B of Fig. 3, all of the figuring warp-threads 2 are up, and the binder threads are same as for the first shot, Fig. 3. The warp-threads in Fig. 4 are in positions the reverse of those shown in Fig. 3. Figs. 3 and 4 will make a dark shading with the yellow weft on the face and a plain red on the back. If the red weft be thrown on the face, as shown in Figs. 9 and 10, a darker shade will be given, and the yellow weft will show on the back. Figs. 5 and 6 show a shading in which all the figuring warp-threads lie between the yellow and red wefts, and only the binding warp-threads appear on face and back. By this set a shading of red or yellow weft may be made on one or both sides of the cloth. Figs. 7 and 8 show a shading in which both the yellow and red wefts are picked into the same "sheds." This set, Figs. 7 and 8, will make a checker pattern on both sides of the cloth, showing a mixture of red and yellow wefts. Figs. 9 and 10 show the same sheds as Figs. 3 and 4, but a change of the wefts, the red showing on the face and the yellow on the back. Figs. 11, 12, 13, and 14 show a set of eight shots. In these shots the weft shows but little on the face; but the warp-threads show in heavy black corded twills, the weft in yellow dots, and the back will be red. For the first shot of yellow weft, Fig. 11, the binder warp-threads are evenly divided—half up and half down—and of the figuring warp-threads the first six are up, the next two down, the next six up, and the next two down. For the second shot, red weft, Fig. 11, the figuring warp-threads are all up, and the binding warp-threads have not changed from the first shot, Fig. 11. For the third shot, yellow weft, Fig. 12, the binder warp-threads are evenly divided—half up and half down—and show the reverse to what is shown in Fig. 11—that is, those threads that are shown up in Fig. 11 are shown down in Fig. 12. Of the figuring warp-threads the first four are up, the next two down, the next six up, the next two down, the next two up. For the fourth shot, red

weft, Fig. 12, all the figuring warp-threads are up, and the binder-threads have not been changed from the position for the third shot, Fig. 12. For the fifth shot, Fig. 13, (yellow weft,) the binder warp-threads have changed or reversed from position shown in Fig. 12; but they show half up and half down. The 60 figuring warp-threads show the first two up, the next two down, the next six up, and the next two down, and the next four up. For the sixth shot of weft, (red,) Fig. 13, all the figuring warp-threads are up, and the binder 65 warp-threads have not changed from the position for the fifth shot, Fig. 13. For the seventh shot, (yellow weft,) Fig. 14, the binder warp-threads have changed from the position shown in Fig. 13, but half are up and half are 70 shown down. Of the figuring warp-threads the first two are down, the next six are up, the next two down, the next six up. For the eighth shot, Fig. 14, (red weft,) all the figuring warp-threads are up, and the binder warp- 75 threads have not changed from the position for the seventh shot of Fig. 14.

It is obvious to any one skilled in the art of weaving that more than two colors of wefts may be used, and these wefts, as desired, may 80 be thrown on the face or back, or together, and a variety of shades in the figures may be made with a few colors.

In the foregoing description I have described my invention as produced in a Jacquard machine; but the binding warp-threads may be mounted in two heddles, working two shots up and two shots down, and this, with the harness-cords for each pair of figuring-warp- 85 connected to one needle will double the capacity 90 of the machine.

I do not broadly claim producing a variety of shades of color by the interweaving of warp and weft threads of different colors; but

What I claim, and desire to secure by Let- 95 ters Patent, is—

The combination of two or more wefts, each of a different color, with figuring warp-threads, and a binder warp-thread between the two figuring warp-threads of each pair, as shown, de- 100 scribed, and for the purpose specified.

DAVID B. KERR.
